CLAIM

The ornamental design for an endoscopic curette with retractable suction tip, as shown and described.

DESCRIPTION

FIG. 1 is a front view of an endoscopic curette with retractable suction tip showing our new design;

FIG. 2 is a right side view thereof, the left side being identical;

FIG. 3 is a rear view thereof;

FIG. 4 is a top view thereof;

FIG. 5 is a bottom view thereof; and,

FIG. 6 is a front view thereof, shown with the suction in extended position.
